UNITED STATES PATENT OFFICE.

CHARLES I. PIGFORD, OF MISSISSIPPI CITY, MISSISSIPPI.

CRAYON-HOLDER.

No. 801,101.

Specification of Letters Patent.

Patented Oct. 3, 1905.

Application filed December 13, 1904. Serial No. 236,744.

To all whom it may concern:

Be it known that I, CHARLES I. PIGFORD, a citizen of the United States, residing at Mississippi City, in the county of Harrison and State of Mississippi, have invented new and useful Improvements in Crayon-Holders, of which the following is a specification.

This invention relates to crayon-holders, and has for its objects to produce a simple inexpensive device of this character in which the crayon will while in use be held firmly in position and may as it becomes worn be readily fed forward to marking position and one wherein the device may when not in use be carried in the pocket of the operator without soiling his clothes.

To these ends the invention comprises the novel features of construction and combination of parts more fully hereinafter described.

In the accompanying drawings, Figure 1 is a sectional elevation showing one form of embodiment of the invention. Fig. 2 is an edge view of one of the clamping arms or members. Fig. 3 is a side elevation, partly in section, of a modified form of casing, showing the parts thereof disconnected. Fig. 4 is an elevation showing a modified embodiment of the clamping device removed from its casing. Fig. 5 is a plan view of the retaining-ring employed in connection with the clamping device shown in Fig. 4.

Referring to the drawings, and particularly to Figs. 1 and 2, it will be seen that the improved holder comprises an outer casing 1 and a crayon-clamping device 2, the casing being provided with a removable cap 3.

The casing 1, which is preferably composed of thin sheet metal, is of tubular form and provided at one end with external threads 4 for engagement by similar internal threads 5, formed upon the cap 3, whereby the latter is detachably engaged with the body of the casing, while the latter has its normally lower end merged into a reduced conical portion 6, the walls of which converge outwardly and terminate in an opening 7, there being formed at the center of the cap 3 an internal bearing lug or projection 8, having a substantially semispherical recess or seat 9 formed therein.

The device 2 preferably consists of a plurality of spring-engaging members or arms 10, composed of sheet-steel and each bent or otherwise shaped to produce at its inner end a substantially semicircular portion 11 and at its outer end an offset inclined engaging portion or finger 12, these fingers being adapted,

when the parts of the clamping device are assembled, to converge relatively and conform to the conical portion 6 of the casing. The terminals of the curved portions 11 of the arms are overlapped and connected together by means of a bolt or other fastening member 13, of non-circular form in cross-section, and provided with a semispherical head 14, which in practice has bearing in the seat 9 on 65 the cap.

In practice the stick of chalk, crayon, or other marking material is arranged in the clamping device 2 between the spring-arms 10, with its active end projected beyond and clamped between the fingers 12, the latter being acted upon to maintain them in clamping engagement by means of the conical portion 6 of the casing, through which they project, as illustrated in Fig. 1, the fingers being projected a greater or less distance through the opening 7 to increase or decrease the clamping pressure by adjusting the cap 3 upon the body of the casing. This adjustment is effected by securing the cap onto the casing, 75 and during the rotation of the cap incident to the adjusting operation a smooth bearing is afforded between the cap and device 2, owing to the semispherical head of the fastening member being situated in the seat 9. 85

In the form of device illustrated in Figs. 3 to 5 the body 1' of the casing has at its normally upper end a reduced portion or neck 15, provided with angular seats for the reception of pins 16, projecting from the inner face 90 of the cap, these seats being preferably inclined from the outer edge of the neck toward its point of union with the body and each comprising, by preference, a primary portion or groove 17, in which the corresponding pin 16 initially seats, and a secondary portion or slot 18, forming a continuation of the groove and with which the pin may be engaged. There is formed at the juncture of the groove and slot a shoulder 19 100 and at the inner terminal of the slot a shoulder 20.

The engaging device 2' is similar in construction to that above described, except that the fastening member 13' is of circular form 105 in cross-section, while the members 10' are secured against relative rotary movement upon the fastening device 13' by means of a ring or collar 21, having at appropriate intervals seats or recesses 22 for the reception 110 of the arms 10'. In this form of holder the clamping device is arranged within the cas-

- ing, as in the form illustrated in Fig. 1, and the cap secured in place upon the casing through the medium of the pins 16 engaging the inclined seats formed in the neck 15.
- 5 When the parts are assembled, the head 14' seats in the recess 9, and upon the initial adjustment of the cap for actuating the clamping-arms to engage the crayon the pins 16 engage the shoulders 19. When, however, it
- 10 becomes necessary or desirable to project the ends of the clamping-fingers beyond the casing for correspondingly projecting the marking medium and at the same time exerting a firmer clamping action upon the latter, the
- 15 cap is rotated until the pins 16 seat beneath the shoulders 20. Except as herein noted, the device illustrated in Figs. 3 to 5 is identical in construction and operation with that first described.
- 20 From the foregoing it is apparent that I produce a simple device which is admirably adapted for the attainment of the ends in view, it being understood that minor changes in the details herein set forth may be resorted

to without departing from the spirit of the 25 invention.

Having thus fully described the invention, what is claimed as new is—

In a device of the class described, a casing having an open end and a bearing portion, the 30 walls of which converge toward said open end, a clamping device arranged in the casing and comprising a plurality of clamping members having meeting ends and relatively convergent inclined portions adapted to be acted 35 upon by the bearing portion of the casing for moving the members to clamping position, a bearing-head provided at the meeting ends of the clamping members, and a cap adjustably engaged with the casing and having a seat for 40 the reception of the bearing-head.

In testimony whereof I affix my signature in presence of two witnesses.

CHARLES I. PIGFORD.
